REFINING MINERAL OILS

Reuben F. Pfennig and Claude R. Davis, Baytown,
Tex., assignors to Standard Oil Development
Company, a corporation of Delaware

Application April 26, 1940, Serial No. 331,698

2 Claims. (Cl. 196—41)

The present invention relates to the refining of mineral oils. The invention especially relates to the refining of petroleum oils for the production of high quality lubricating oil distillates. In accordance with the present process, petroleum oils, particularly those petroleum oils boiling in the lubricating oil range, are contacted in an initial stage with an anhydrous molten alkali and in a secondary stage are distilled in a manner to produce high yields of products of improved quality.

It is known in the art to refine crude petroleum oils by various procedures in order to produce satisfactory products. For example, in the processing of lubricating oil stocks derived from naphthenic crudes, it is known that certain constituents, such as naphthenic acids and the like, must be removed for the production of neutral distillates. A usual procedure for accomplishing this result is to inject aqueous solutions of sodium hydroxide or equivalent solutions directly into the still, preheater, or fractionating tower and to allow the distillation to proceed in the presence of this alkali. Various modifications of this process are also employed, one of which is to inject dry lime into the preheater or still in order to neutralize acidic compounds which results in an improvement in the color of the refined oil. It is also known to pass mixtures of petroleum vapors and steam through a strong aqueous alkali solution or through a fused body of sodium hydroxide at elevated temperatures. Another practice is to contact petroleum vapors with fused caustic in a distillation tower by circulating the liquid caustic over several plates near the bottom of the tower. By operating in this manner, the vapors from the still are passed countercurrently through the liquid caustic, thus neutralizing acidic materials and effecting a color improvement in the distillate. Hydrocarbon oils have also been extracted with aqueous solutions of sodium hydroxide at relatively high temperatures, for example, in the range from about 300° F. to 400° F. and at elevated pressures such as 300 pounds to 400 pounds per square inch. These processes, however, while accomplishing satisfactory results in general, possess certain disadvantages which increase operating difficulties and render the operation relatively expensive. A distillation operation conducted in the presence of a solution of sodium hydroxide tends to cause deposition of the caustic on the

wall of the equipment and heating means, which materially decreases heat transfer rates and increases operating costs. Furthermore, it is necessary to frequently clean the equipment, thus 5 substantially decreasing its yearly throughput. Other disadvantages encountered in current processes are the extensive pressure drops which are incurred, particularly in vacuum distillation operations, as well as the formation of emulsions 10 which are difficult to break.

We have now discovered an improved process for the production of high yields of improved quality products which have a better color and color stability than has heretofore been secured 15 by known processes, which comprises an initial stage in which the feed oil is first contacted with a fused alkali and a secondary stage in which the treated oil is distilled under controlled conditions. Our process produces oils which finish 20 to a low neutralization value and which have exceptionally good cast and high color stability. In accordance with our process, the feed stock is contacted in the liquid phase at approximately atmospheric pressure with an anhydrous caustic molten alkali which may or may not be mixed 25 with another anhydrous material capable of lowering its fusion point, but which does not change its chemical activity. After contact of the feed stock in an initial stage, the oil is distilled in a secondary stage under controlled 30 conditions to secure the desired products.

The process of our invention may be readily understood by reference to the attached drawing illustrating modifications of the same. Crude oil, 35 which for the purpose of the description is taken to be a naphthenic crude, is withdrawn from crude storage tank 1 and introduced into furnace 2 by means of line 3 and pump 4. The oil is heated in furnace 2 and then introduced into 40 distillation tower 5 by means of line 6. Temperature and pressure conditions are regulated on distillation tower 5 adapted to remove overhead by means of line 7 hydrocarbon constituents boiling in the motor fuel, kerosene, and gas oil 45 boiling ranges. It is to be understood that distillation tower 5 may comprise any number of units arranged in any desirable manner. The residual oil substantially free of hydrocarbon constituents boiling in the motor fuel, kerosene, 50 and gas oil boiling ranges is withdrawn from distillation tower 5 by means of line 8 and pump 9. The residuum is then mixed with a fused

alkali which is introduced by means of line 10 and the mixture introduced into mixer 11. For purposes of description, the fused alkali is taken to be an anhydrous mixture of sodium hydroxide and sodium carbonate. The mixture comprising residual oil, fused sodium hydroxide, and sodium carbonate is withdrawn from mixer 11 by means of line 12 and introduced into settling zone 13. Settling zone 13 is so designed that the residual oil is in contact with the fused alkali for an optimum time period at the desired temperatures. The desired temperature in settling zone 13 is maintained by heating means 14 comprising lines 15 and 16. The fused alkali mixture is withdrawn from settling drum 13 by means of line 17 and recycled to the mixer as described by means of recycle pump 18. Spent fused alkali may be withdrawn from the system by means of line 19, while fresh or make-up alkali may be introduced from make-up alkali drum 20 by means of pump 21 and line 22. The desired temperature is maintained in make-up drum 20 by means of heating coil 23 which comprises lines 24 and 25. The alkali contacted oil is withdrawn from settling zone 13 by means of line 26, passed through furnace 27 and introduced into distillation tower 28. Temperature and pressure conditions of distillation tower 28 are adapted to remove overhead by means of line 29 the desired products and to remove by means of line 30 a residue. It is to be understood that distillation tower 28 may comprise any number of towers arranged in any desirable manner and that one or more side streams may be segregated.

The process of the present invention may be widely varied. The invention comprises processing feed oils in a two-stage operation, the initial stage of which comprises contacting the feed oil in the liquid state with a fused alkali, followed by distilling the alkali contacted oil in a secondary distillation stage. The process may be adapted to the treatment of any feed oil. The invention, however, is particularly adapted for the processing of oils containing naphthenic bodies, especially for processing lubricating oil stocks derived from naphthenic crudes. In accordance with the preferred modification of the present invention naphthenic crude oils are distilled at substantially atmospheric pressures under conditions to remove overhead fractions boiling in the motor fuel, kerosene and gas oil boiling ranges and to produce a residuum substantially free of these constituents which is then processed in accordance with the present invention. In general, it is preferred that the residuum should have an initial boiling point above 450° F., preferably in the range above 550° F.

Although any anhydrous fused alkali may, under certain conditions, be employed, we prefer to utilize anhydrous alkali metal hydroxides, such as sodium hydroxide and potassium hydroxide. An especially desirable treating agent comprises a mixture of sodium hydroxide and potassium hydroxide, particularly when the concentration of the sodium hydroxide is in the range from about 25% to 85%. In general, the most satisfactory operation is secured when the sodium hydroxide, potassium hydroxide mixture comprises from 45% to 55% of sodium hydroxide.

Other desirable alkali mixtures comprise sodium hydroxide admixed with various anhydrous inorganic salts which are capable of lowering the fusion point of the sodium hydroxide. Particularly desirable salts are sodium carbonate, sodium sulfide, sodium bromide, sodium iodide and sodium sulfate. An especially desirable alkali mixture utilizing sodium hydroxide comprises a mixture of sodium hydroxide and anhydrous sodium carbonate. When employing this mixture, it is desirable to use at least 75% sodium hydroxide, preferably from 85% to 95% sodium hydroxide. A particularly desirable mixture comprises 92% sodium hydroxide and 8% sodium carbonate. The alkali should be substantially anhydrous. In no instance is it desirable that the moisture content of the treating alkali or alkali mixture exceed about 2.0%. In general, the moisture content of the alkali treating agent should be below about 0.5% and should preferably be anhydrous.

The time of contact between the fused anhydrous alkali mixture and the oil will depend upon the feed oil being treated, the particular alkali or alkali mixture employed, as well as upon the temperature at which the oil is treated. For example, when treating a feed oil derived from a naphthenic crude and which boils in the range above about 500° F., it is preferred to contact the same for a period of from 5 to 25 minutes, preferably from 10 to 20 minutes, at a suitable temperature ranging between 370° F. and 700° F., preferably from about 500° F. to 550° F. The pressures employed seldom should exceed one or two atmospheres and, in general, the operation should be conducted at about atmospheric pressure. The quantity of anhydrous fused alkali used per volume of oil likewise will vary considerably. In general, the quantity of fused alkali will vary in the range from about 0.1 volume to 3 volumes of alkali per volume of oil. In general, it is preferred to employ from 1.0 to 1.5 volumes of anhydrous fused alkali per volume of oil. The alkali treated oil after separation from the alkali is then heated to a temperature of about 600° F. to 700° F., and discharged preferably into the vacuum distillation equipment, in which the respective streams are segregated from the residue.

In order to further illustrate our invention, the following operations are given which should not be construed as limiting the same in any manner whatsoever:

Operation I.—A coastal crude having a neutralization value equivalent to 1.20 milligrams of potassium hydroxide per gram of oil was distilled under atmospheric pressure at a liquid still temperature of 600° F. for the removal of the light products such as naphtha, kerosene and gas oil. One volume of the resultant residuum was then intimately contacted with about 1.5 volumes of a molten caustic alkali reagent consisting of 92% NaOH and 8% Na₂CO₃ by weight (fusion point about 510° F.) for about 10 minutes at a temperature of 550° F. After settling and separating the oil from the reagent, the caustic treated oil was charged to a vacuum still and distilled into finished overhead fractions having the following properties:

Vis. at 100° F., S. S. U.	88	100	128	240	286	728	823	877	1,534
Color, Tag-Robinson plus	17	17	17	17	17	11.75	12	11	9
Colorhold (16 hrs. at 250° F.), Tag-Robinson	16	16.25	15.25	12	12.25	10	10.25	10	7.75
Neutralization value	0.01	0.02	0.03	0.03	0.03	0.01	0.03	0.03	0.01

For purposes of comparison, a similarly topped crude was vacuum distilled over 200% of the theoretically required amount of caustic injected into the still as a 50° Baumé aqueous solution. The following oils were obtained:

Vis. at 100° F., S. S. U.	64	114	289	907	1,674	145	1,039
Color, Tag-Robinson	17	14.25	11.75	9.25	8	17	9
Colorhold (16 hrs. at 250° F.), Tag-Robinson	1	0.5	0.62	0.75	0.5	10.5	2.25
Neutralization value	0.02	0.03	0.02	0.02	0.02	0.02	0.02

It will be noted from the above that the oils produced in accordance with the usual method of distilling over an excess of caustic require additional chemical and physical treatment to render them color stable, whereas those produced in accordance with our invention are color stable and require no further treatment.

Operation II.—A batch treat was made employing approximately 10 volumes of reduced coastal crude to 1 volume of a molten caustic alkali mixture consisting of 92% sodium hydroxide and 8% sodium carbonate by weight. The oil was intimately contacted with the reagent for about 10 minutes at a temperature of 550° F., after which it was allowed to settle. The treated oil was then fractionated into two overhead cuts and a residuum. The overhead products had the following properties:

Viscosity at 100° F., S. S. U.	144	1,009
Color, Tag-Robinson	17	9.25
Colorhold (16 hrs. at 250° F.), Tag-Robinson	12.25	6.5
Neutralization value	0.014	0.03

A comparison of these data with those presented under Operation I shows that the use of greater amounts of reagent renders the oil more color stable; nevertheless, this relatively small treat with molten alkali produced oils far superior in color stability to those produced by the usual method of distilling over caustic.

Operation III.—A study was made of the effect treating temperatures and times of contact have on the color and color stability of molten alkali treated oils. Several batch treats were made on a reduced coastal crude employing a molten mixture of alkali consisting of 92% of sodium hydroxide and 8% sodium carbonate as the reagent in each case but with varying temperatures and times of contact. In each of these treats, approximately one volume of oil was intimately contacted with 1.5 volumes of the molten reagent for the predetermined time at the selected temperature. Each of the several batches of treated reduced crude was then distilled into three overhead cuts and a residuum. The following inspections are typical of those obtained on the lube stocks produced in these operations:

	Distillate cut, per cent reduced crude					
	15-40		40-69		40-71	
Contact time with Reagent minutes	10	10	10	10	20	30
Temperature of contact °F.	550	650	650	550	550	550
Viscosity at 100° F., S. S. U.	125	150	987	877	791	771
Color, Tag-Robinson	17	17	9.25	11	10.75	10.5
Colorhold (16 hrs. at 250° F.), Tag-Robinson	15.25	10.75	7.25	10	9.25	9.25

The above data indicate that the lowest treat-
ing temperature and the shortest time of contact
available with good mixing gave the best oils
although increased time of contact at the lower
temperature did not appreciably harm the color
stability.

Operation IV.—The following operation illustrates the suitability of a mixture of sodium hydroxide and potassium hydroxide as a molten alkali treating reagent for the production of neutral and relatively color stable lubricating oils

from naphthenic crudes. In these operations, two batches of reduced Coastal crude were intimately contacted with a molten alkali mixture consisting of 51% NaOH and 49% KOH for 10 minutes, employing a contact temperature of 420° F. in one instance and 550° F. in the other. The volume ratio of oil to reagent was approximately 1 to 1.5 in each case. Each of these treated batches of reduced crude was distilled under vacuum to yield lube oils having the following properties:

25		Treating temperature			
		420		550	
		Viscosity at 100° F., S. S. U.	130	861	132
30	Color, Tag-Robinson	17	11.75	17	13.75
	Colorhold (16 hrs. at 250° F.), Tag-Robinson	17	10	16.25	10.75
	Neutralization value	0.01	0.03	0.01	0.035

Although in these operations only one particular mixture of sodium hydroxide with potassium hydroxide was employed as the reagent, it is evident that other mixtures can be used equally as well to produce high quality oils so long as the fusion point is not sufficiently high to cause cracking of the oil.

Operation V.—A batch of reduced Coastal crude was contacted with molten sodium hydroxide for 10 minutes at 650° F. The ratio of oil to reagent employed was approximately 1 to 1.5 by volume, respectively. The lube distillates vacuum distilled from this treated reduced crude had the following properties:

50	Viscosity at 100° F., S. S. U.	140	946
	Color, Tag-Robinson	17	10.5
	Colorhold (16 hrs. at 250° F.), T.-R.	13	9.25
	Neutralization value	0.03	0.02

Although these oils are relatively color stable, their quality is not quite as good as that of the oils treated at lower temperatures with either a mixture of sodium hydroxide with sodium carbonate or a mixture of sodium hydroxide with potassium hydroxide.

Operation VI.—A reduced Panhandle crude was contacted for 10 minutes at 550° F. with a molten caustic alkali consisting of 92% NaOH and 8% Na₂CO₃. The ratio of oil to reagent was approximately 1 to 1.5 by volume, respectively. By vacuum distillation, oils with the following proper-

ties were obtained from this treated reduced Panhandle crude:

Viscosity at 100° F., S. S. U.	46	94	Solid
Color, Tag-Robinson	19.25	14.25	9.25
Colorhold (16 hrs. at 250° F.), T.-R.	14.5	11.25	3.5
Neutralization value	0.01	0.007	0.02

By way of comparison, the above oils had much better color stabilities than did similar oils prepared from reduced Panhandle crude which had not been subjected to any treatment other than distillation. The following inspections are representative for such untreated oils:

Viscosity at 100° F., S. S. U.	42	85	Solid
Color, Tag-Robinson	20.5	16	8.5
Colorhold (16 hrs. at 250° F.), T.-R.	11.75	4.75	0.75
Neutralization value	0.12	0.14	0.16

Additional tests were conducted for stabilizing the color of cracked oils by molten alkali treatment. Although improvement in their properties was realized, it was necessary to subject the cracked oils to other chemical treatment, such as

sulfuric acid, in order to obtain finished oils having the desired color and color stability.

The invention claimed is:

1. Process for the production of oils of improved color stability and cast and low neutralization value from feed oils boiling in the range above about 500° F. and derived from naphthenic crude oils comprising contacting said feed oils in the liquid state in an initial stage at a temperature in the range from about 500° F. to about 550° F. and at atmospheric pressure for a period of from about 10 minutes to about 20 minutes with an anhydrous fused alkali, separating the treated oil from the fused alkali and subjecting the same to a distillation operation in a secondary stage under conditions adapted to remove high quality products overhead.
- 10 2. Process in accordance with claim 1, in which said fused alkali comprises a mixture of sodium hydroxide and sodium carbonate.
